UNITED STATES PATENT OFFICE.

MATTHIAS BROCK, OF BOSTON, MASSACHUSETTS, ASSIGNOR TO THE MCKAY & COPELAND LASTING MACHINE COMPANY, OF PORTLAND, MAINE.

MACHINE FOR SHAPING COMB TACK-STRIPS.

SPECIFICATION forming part of Letters Patent No. 329,009, dated October 27, 1885.

Application filed August 31, 1885. Serial No. 175,743. (No model.)

To all whom it may concern:

Be it known that I, MATTHIAS BROCK, of Boston, county of Suffolk, and State of Massachusetts, have invented an Improvement in 5 Apparatus for Shaping and Indenting the Heads and Connecting-Webs of Comb Tack-Strips, of which the following description, in connection with the accompanying drawings, is a specification, like letters on the drawings 10 representing like parts.

This invention has for its object to indent or shape the head-forming flange and web of a comb tack-strip to produce heads of substantially uniform size and contour.

15 In accordance with my invention, a flanged strip of metal, provided with teeth is passed between two disks or wheels having wedge-shaped punches, which act to indent the opposite sides of the web connecting the shanks, 20 the indentations being in line with the spaces between the shanks of the tacks, the flanged part or top of the web being indented transversely by a punch, the disks or wheels acting to feed the strip through the machine intermittently.

25 My invention consists, essentially, in the combination, in a comb tack-strip machine, of two rotating disks or wheels between which the strip is fed or carried, the said wheels having punches to cut into and indent the sides 30 of the web below its flanged part or top, which is to form the head, and which is struck by the driver of the machine employed to drive the tacks. In connection with the above I employ 35 a vertically-moving punch, which acts to cut into or indent transversely that part of the web which constitutes the head, and is acted upon by the driver that drives the separate tacks, such cutting or indenting of the web 40 and flanged part making it easy to separate the tacks singly from the comb-strip.

Figure 1, in front elevation, shows a machine embodying my invention; Fig. 2, a left-hand end elevation of Fig. 1; Fig. 3, a top or plan 45 view of Fig. 2 below the line xx , the cap-plate and part of one of the indenting wheels or disks being broken out; Fig. 4, a side elevation of one of the disks or wheels removed from the machine; Fig. 5, a cross-section of Fig. 4; 50 Fig. 6, side, top, and end views of one of the web-indenting punches removed; Fig. 7, a cross-section of a piece of comb tack-strip;

Fig. 8, a top view of Fig. 7, and a section thereof in the line $x^2 x^2$.

The frame-work A, of suitable shape to sustain the working parts, has mounted in it the main shaft A', provided with usual fast and loose pulleys, the said shaft also having fast on it two cams or eccentrics, $a a$, which are embraced by the yokes a' of the slide-rods B B', having at their upper ends the cross-head B², to which, by the screw b, is attached the punch b', which acts upon and indents transversely the flanged top or head-forming part of the comb tack-strip. The openings in the 65 yoke a' , being considerably larger than the eccentric a , as shown in Fig. 1, enable the slide-bars to be moved vertically in guides in the frame-work.

The bed C of the machine has erected on it 70 two studs, c c, each of which receives loosely upon it a ratchet-toothed wheel, c², having attached to its top a wheel or disk, c³, cut or grooved radially at its periphery to form pockets to receive a series of punches, d, (see 75 Fig. 6, where the said punches are shown removed,) each punch having a portion of its end near its upper side beveled or pointed, as shown, to cut into and indent the web of the comb-strip, or that part of the comb-strip 80 immediately below the head, and between it and the shanks of the tacks, the punches d d' indenting or cutting into the web at each side, as best shown in Fig. 8, nearly separating the said web in line with the spaces between the 85 shanks of the tacks. The wheels c³ are in practice covered by plates e, which latter aid in keeping the punches in position in the wheels c³.

The slide-rod B (see Figs. 2 and 3) at a point 90 above the bed C is cut away, as at 2 2, to form cam-shaped recesses, into which enter rolls at the ends of slides g, normally kept pressed toward the said cam-shaped recesses by springs 4, the said slides each carrying a pawl, h h, acted upon by a spring, h', the movement of 95 the said slides at each stroke of the cross-head causing the said pawls to engage the ratchet-teeth of the wheels c² c², and rotate the same and the wheels c³ intermittently.

Referring to Fig. 7, the indentations marked 100 3 are those produced by the punch b', while in Fig. 8 the indentations 5 in the web 6 are those made by the punches d d'.

The comb tack-strip to be operated upon

will be inserted, preferably, through the guide m m' , the latter in practice being covered, and thence between the wheels or disks referred to into the guides m^2 and m^3 , being delivered from the latter in condition ready to be placed into a "hand-tacker" or other nailing-machine, to be employed to sever the tacks one after the other from the comb tack-strip and to drive the same.

10 I do not broadly claim the employment of toothed wheels by which to support or to feed a comb tack-strip while it is being headed, as I am aware that that is old.

I claim—

15 1. The combination, in a machine for indenting comb tack-strips, of two disks or wheels provided with radially-placed punches to act

upon and indent from each side the connecting web of the comb tack-strip in line with the spaces between the shanks of the tacks, substantially as described.

2. The wheels or disks provided with punches to cut into or indent the connecting web of a comb tack-strip, combined with a punch to cut partially into or indent the head forming flange of the said comb tack-strip, substantially as described.

In testimony whereof I have signed my name to this specification in the presence of two subscribing witnesses.

MATTHIAS BROCK.
